US0D1072221S

(12) **United States Design Patent** (10) **Patent No.:** **US D1,072,221 S**
(45) **Date of Patent:** **** Apr. 22, 2025**

(54) **FILTER**

- (71) Applicant: **SteriCUBE Surgical Systems, LLC**, Grapevine, TX (US)
- (72) Inventors: **Michele Mauzerall**, St. Petersburg, FL (US); **Maryellen Keenan**, Nutley, NJ (US)
- (73) Assignee: **SteriCUBE Surgical Systems, LLC**, Grapevine, TX (US)
- (**) Term: **15 Years**
- (21) Appl. No.: **29/949,405**
- (22) Filed: **Jun. 26, 2024**

Related U.S. Application Data

- (63) Continuation of application No. 16/442,234, filed on Jun. 14, 2019.
- (51) **LOC (15) Cl.** **24-04**
- (52) **U.S. Cl.**
USPC **D12/162**
CPC **A61L 2/07** (2013.01); **A61L 2202/24** (2013.01)
- (58) **Field of Classification Search**
USPC D23/209, 210, 355–369, 370, 386–388; D24/162

(57)

CLAIM

The ornamental design for a filter, as shown and described herein.

DESCRIPTION

FIG. 1 is a front view of a filter embodying our design; and, FIG. 2 is a top, front, left-side perspective view thereof. The broken lines shown in FIG. 2 represent portions of the sterilization unit that form no part of the claimed design.

1 Claim, 2 Drawing Sheets
